UNITED STATES PATENT OFFICE.

WILLIS N. GRAVES, OF ST. LOUIS, MISSOURI, ASSIGNOR OF ONE-HALF TO
THE HYDRAULIC PRESS BRICK COMPANY, OF SAME PLACE.

BRICK-KILN.

SPECIFICATION forming part of Letters Patent No. 292,427, dated January 22, 1884.

Application filed January 30, 1883. (No model.)

To all whom it may concern:

Be it known that I, WILLIS N. GRAVES, of the city of St. Louis, in the State of Missouri, have invented a certain new and useful Improvement in Brick-Kilns, of which the following is a full, clear, and exact description, reference being had to the accompanying drawings, forming part of this specification, and in which—

10 Figure 1 is part in top view and part in horizontal section, taken on line 1 1, Fig. 2: Fig. 2 is a vertical section taken on line 2 2, Fig. 1. Fig. 3 is a front view, showing the gas-flues in transverse section, taken on line 3 3, Fig. 1. Fig. 4 is a vertical section taken on line 4 4, Fig. 5. Fig. 5 is a horizontal section taken on line 5 5, Fig. 4; and Fig. 6 is a detail transverse vertical section taken on line 6 6, Fig. 5.

15 My present invention relates to a kiln in which gas is used as fuel; and my invention consists in points of novelty hereinafter fully described and claimed.

20 Referring to the drawings, A represents a number of kiln-chambers separated by pier-walls A', and one or more series (I have shown two) may be placed side by side and connected by suitable flues and pipes, as hereinafter described.

25 B represents a gas-generator. (See Fig. 1.) There would preferably be one for each series, communicating with a main gas-flue, C, which has branch flues C', extending at right angles along the pier-walls, one for each kiln-chamber, as shown plainly in Fig. 4. The branch flues near the main flues are made deeper than they are after entering the kiln, (see Fig. 6,) and here they are provided with horizontal diaphragms D, beneath which the gas enters

30 from the main flue, provided with openings D', which form seats for valves D'', whose stems extend up through the tops of the flues, where they can be reached to operate the valves, and thus it will be seen that the amount of gas 35 entering any one branch flue can be controlled at will or entirely closed off without interfering with the other branch flues. From the branch flues the gas escapes into the combustion-chambers E through openings E' in the

bottom of the chamber, which can be partly 50 or altogether closed at will by tile-blocks E'', which act as valves, one for each opening, and can be operated by a suitable instrument inserted into the combustion-chambers by opening the doors E'', and thus the amount of gas 55 entering any part of a combustion-chamber can be controlled. The air for combustion preferably passes from a kiln-chamber down through the open floor into the distributing-flues F, (see Fig. 5,) which communicate with a flue, G, beneath and communicating with a flue, H, by means of openings G', which can be partly or wholly closed by tile-blocks G'', operated by means of a suitable instrument inserted into the flue H by opening its door 60 H''. The flues H communicate with the combustion-chambers by means of openings A'' in the pier-walls between the kiln-chambers, and by opening or closing the valves between the flues G and H it will be seen that the amount 65 of air entering any part of the combustion-chamber can be controlled at will, there being an opening, A'', for each opening G', as shown. The flues G communicate at one end with a main flue, I, that leads to the chimney or uptake J, and they are provided with dampers or valves G'', so that the communication can be regulated or entirely closed. From the chamber E the products of combustion pass 70 up through a passage, K, shut off from the main kiln by a bridge-wall, K', and down through the mass of bricks, (see arrows, Fig. 4,) and from there into the flues G, as described, from where they escape either into the main flue I or into the next kiln-chamber 75 80 by way of the flues H and openings A''; or, if it is the last kiln of a series, they may, as shown in Fig. 4, escape into an end flue, L, through openings L' in the end of the kiln, each series being provided with such a flue, 85 90 which communicate with a flue, M, beneath and connecting them, and thus the heat from one series may be transferred to the other.

When a kiln has been burned, the heat can be made use of for drying a kiln of green bricks 95 by taking the heat from the top of the chamber of burned bricks through passages N into flues N', which communicate with main flues

N². The passages N are controlled by valves N⁴, whose stems extend up through the tops of the flues N', and by these valves the heat may be discharged from the main flue N² into any part of any kiln-chamber desired.

I have shown four openings on each side of each kiln-chamber communicating with the flues N'. (See Fig. 5.) The main flues N² of each series may be connected by pipes O, (see Figs. 1 and 2,) so that this heat can be transferred from one series to the other. The bridge-walls K' are strengthened by ties K². (See Figs. 4 and 6.)

P represents openings in the tops of the kiln-chambers, closed by valves P', to ventilate or allow the escape of heat when desired. If desired, this above-mentioned hot air can be taken from one kiln-chamber into one adjoining it without passing into the main flue N', as will be plainly seen, and the air thus supplied, if the kiln into which it enters is undergoing the burning process, may assist in the more thorough combustion of the gases, practically forming a second combustion-chamber near the top of the passage or flue K.

I have shown and described the gas-flues C' as being beneath the combustion-chambers E'; but I do not wish to confine myself to such a location, as they may be at one side or elsewhere.

I claim as my invention—

1. In a brick-kiln, the combination of a main chamber, A, having side walls and a perforated floor, a gas-flue on one side of the chamber, beneath the floor, a bridge-wall on one side of the chamber, above the floor, forming a combustion-chamber, E, in communication with the flue and directing the products of combustion to the top of the main chamber, and valves to control the supply of gas to the combustion-chamber, as set forth.

2. In a brick-kiln, the combination of a main chamber, A, having side walls and a

perforated floor, a main gas-flue, C; branch flue C' on one side of the chamber, beneath the floor, diaphragm D between the flues, having opening D' and valve D², and bridge-wall K on one side of the main chamber, above the floor, forming combustion-chamber E over the branch flue, as set forth.

3. In a brick-kiln, the combination, with the main chamber having open floor, of the distributing-flues F and the lower flue, G, beneath the floor, upper flue, H, above the floor, having openings to the lower flue beneath, and the pier-walls, having openings A² to connect another main chamber with the upper flue, as set forth.

4. In a brick-kiln, the combination, with a main chamber having an open floor in communication with distributing-flues, of the gas-flue on one side, beneath the floor, a combustion-chamber above the gas-flue and floor, a lower flue on the other side in communication with the distributing-flues, and an upper flue above the floor, and lower flue, having suitable outlet, as set forth.

5. In a brick-kiln, the combination, with two main chambers, A, A, of the pier-wall A', formed with longitudinal flue N' at top, connected with the main chambers by passages N, controlled by suitable valves, as set forth.

6. In a brick-kiln, the combination, with a series of main chambers divided by pier-walls A', each having a flue, N', at top, and passages N, connecting the adjoining main chambers with the flue, of the main flue connecting the top flues, as set forth.

7. In a brick-kiln, the flues O, connecting the main flues, in combination with the top flues of series of main chambers, as set forth.

WILLIS N. GRAVES.

In presence of—

E. C. STERLING,
GEO. K. KNIGHT.
